FRANK H. PRESCOTT, OF ANDERSON, INDIANA, ASSIGNOR TO GENERAL MOTORS CORPORATION, A CORPORATION OF DELAWARE.

ENGINE-STARTING APPARATUS.

Application filed July 28, 1924. Serial No. 728,587.

This invention relates to the type of electrical starting apparatus for internal combustion engines which includes an electric motor operating a normally demeshed pinion adapted to mesh with an engine gear. Manual means are employed to shift the pinion into engagement with the engine gear and to close the motor switch. To provide for registration of gears to secure meshing, the manual means includes a pedal and a spring connection between the pedal and the pinion so that, in case of tooth abutment arresting the meshing movement of the pinion, the pedal may be moved to close the motor switch. The motor will then rotate the pinion to register it for meshing with the engine gear, and the spring which has been stressed by movement of the pedal will be released to move the pinion into mesh with the engine gear.

One of the objects of the invention is to improve the spring connection referred to in a manner to enable the apparatus to be made at lower cost.

The present invention is susceptible of various applications but is disclosed in connection with a form of engine starting apparatus described and claimed in the co-pending application of George W. Elsey, Serial No. 728,584 filed July 28, 1924.

Further objects and advantages of the present invention will be apparent from the following description, reference being had to the accompanying drawings, wherein preferred embodiments of one form of the present invention are clearly shown.

Figs. 1, 2 and 3 of the drawings are fragmentary side elevations, partly in section, showing one form of starting apparatus in three positions, respectively,—normal or non-operating position, engine-cranking position, and position for effecting, in case of tooth abutment, preliminary rotation of the motor to facilitate gear enmeshment. Fig. 4 is a sectional view on an enlarged scale taken on the line 4—4 of Fig. 3. Figs. 5 and 6 are sectional views on the lines 5—5 and 6—6, respectively, of Fig. 4; and Fig. 7 is a fragmentary view showing a modified form of gearing adapted to be used in combination with the present invention.

In the drawings, the engine to be started is represented by a flywheel gear 20 adapted

to be driven and to drive a motor pinion 21, which is threadedly engaged by the spiral splines 22, formed on a motor shaft 23, which supports the armature 24 of an electric motor 25. The motor 25 includes a field frame 26 secured to a gear housing 27, the frame 26 supporting a bearing for the left end (not shown) of the shaft 23, and the housing 27 providing a bearing 28 for the right end of the shaft 23. The hub 29 of pinion 21 is provided with flanges 30 and 31, which define a groove 32 which is engaged by the arms 33 of a bifurcated lever provided with a yoke 34 connecting the arms. The lever arms 33 are pivoted upon a rod 35 supported by brackets 36 extending from the housing 27, the rod 35 being retained endwise by its head and by a cotter pin 37.

The mechanism for actuating the lever arms 33, includes a pedal 40 connected by rod 41 with a lever 42. For returning the pedal 40 to position shown in Fig. 1, there is provided a spring 43 located between the pedal 40 and a cup-shaped member 44, through which the rod 41 passes, said member 44 being supported by the floor 45 of the automobile.

The lever 42 includes arms 46 which are pivoted upon the rod 35 and which are connected adjacent their lower ends by a stud 47 which provides a pivot for a latch pawl 48 provided with a hook 49 for engaging a latch plate 50 movable relative to the yoke 34 of the levers 33. The yoke 34 is provided with an opening 51 for receiving the extension 52 of latch pawl 48. The lever arms 33 are each provided with an opening 53 for receiving an end of the latch plate 50 and for guiding said plate during its movements relative to the lever yoke 34.

To the plate 50 are attached spring studs 55, each passing thru a hole 56 provided in the yoke 34 and each provided with a washer 57. A spring 58 surrounds each stud 55 and is confined in an initial state of compression by the washer 57 and the yoke 34, so that the latch plate 50 is yieldingly urged toward the yoke 34 by the action of springs 58.

The flange 30 of hub 29 of gear 21 is normally yieldingly pressed against a stop 60 provided on shaft 23, by a spring 61

having intermediate loop portions 62 bearing against the latch plate 50 and including portions 63 coiled around the pin 35 and having its end portions 64 bearing against a stationary part such as the field frame 26. The spring loop 62 urges the latch plate 50 against the yoke 34, and the lever arms 33 urge the flange 30 against the stop 60.

The latch pawl 48 includes an arm 70 provided with a hole 71 engaged by the end 72 of a spring 73, secured by a screw 74 to the housing 27.

The motor switch 80 includes a plunger 81 located in the path of movement of the end 82 of lever 42. The plunger 81 carries within the switch case a movable contact adapted to engage stationary contacts, one of which is connected with a terminal 83 and the other of which is connected with the motor field circuits. The switch 80 is attached by a screw 84 to the field frame 26. A spring 85 urges the plunger 81 into switch-open position.

The operation of the invention shown in Figs. 1 to 6 inclusive is as follows:

The pedal 40 is depressed to move the lever 42 downwardly and the levers 33 to the right of the drawings, motion being transmitted to levers 33 through the latch pawl 48, latch plate 50 and springs 58. This movement of levers 33 causes the pinion 21 to move toward the engine gear 20. If the gears mesh without tooth abutment, after the pinion 21 has been introduced into mesh with gear 20 by pedal operation, the lever end 82 will engage the plunger 81 and the motor switch will be closed, whereupon the motor will turn the shaft 22 in such direction as to cause the pinion 21 to be moved endwise against a stop 90, which is secured to the shaft 23. A thrust washer 91 is located between the collar 90 and a plane surface provided by the housing 27. Endwise movement of the pinion 21 being arrested by engagement with the collar 90 and by the collar 90 engaging the thrust washer 91, rotation of the motor shaft 23 will cause the engine to be cranked through the gears 21 and 20. During the movement of the pinion 21 into full engagement with the gear 20, the latch pawl 48 has been moved by the operation of spring 73, into the position shown in Fig. 2, so that the pedal 40 is disconnected from the pinion 21. Therefore, when the engine becomes self-operative, the pinion 21 will be automatically demeshed from the gear 20 although the operator has failed to release the pedal 40. The dot-and-dash lines in Fig. 2 show the position of flanges 30 and 31 connected with the pinion 21 and the levers 33 after the pinion 21 has been demeshed. The spring 61 tends to maintain the pinion 21 in demeshed position.

If the teeth of pinion 21 fail to register

with the tooth spaces of gear 20 and tooth abutment takes place as shown in Fig. 3, continued pressure upon the pedal 40 will cause the lever 42 to move into the position shown in Fig. 3 to close the motor switch and to cause the springs 58 to be compressed beyond their initial state of compression. When the motor switch is closed, the motor will operate to produce a preliminary rotation of the shaft 23 to bring the teeth of pinion 21 into registration with the tooth spaces of gear 20. When this occurs the springs 58 will quickly move or "jump" the pinion 21 into engagement with the gear 20.

The pinion 21 is introduced into mesh with the gear 20 by virtue of pressure exerted through or by the springs 58, whether or not tooth abutment occurs beforehand. If tooth engagement has been effected in the manner described, the operation of the motor is used to complete the engagement.

To restore the starter to normal condition shown in Fig. 1, pedal 40 is released to permit the spring 43 to return the lever 42 to normal position. This movement of lever 42 will cause the latch pawl 48 to return to the position shown more clearly in Fig. 5. During its return movement, the projection 52 of lever 48 will move over the latch plate 50 and the spring 73 will cause the hook 49 to re-engage the plate 50.

Referring to Fig. 7, the mechanism shown in Fig. 1 for connecting the pedal 40 with the pinion 21 may be applied to a construction in which the pinion 21 is connected by straight splines 22^a with the shaft 23 and is provided with spiral teeth 21^a for engaging a spiral-tooth engine gear 20^a.

While the forms of embodiment of the invention as herein disclosed, constitutes preferred forms, it is to be understood that other forms might be adopted, all coming within the scope of the claims which follow.

What is claimed is as follows:—

1. Engine starting apparatus comprising, in combination, a motor including a motor frame and gear housing; a pinion for engaging the gear of an engine to be started; a motor switch; a pivot rod supported by the gear housing; a pinion-shifting lever pivoted on said rod and extending within the gear housing; a pedal lever having an arm extending within said housing and an arm for operating the motor switch; means located within said housing for connecting said pedal lever and pinion-shifting lever, including a spring for permitting operation of the pedal to close the switch in case the pinion teeth collide with the teeth of the engine gear.

2. Engine starting apparatus comprising, in combination; a pinion for engaging the

- gear of an engine to be started; a motor for driving the pinion; a motor switch; and manually operable means for moving the pinion into engagement with the engine gear and for closing the switch said means including a pedal operated lever, a pinion shifting lever coaxial with the pedal lever, a rod attached to the pedal lever and movable through an opening in the pinion lever, a shoulder member on the rod, and a coiled spring surrounding the rod and located between the shoulder member and the pinion lever.
3. Engine starting apparatus comprising, in combination, a motor including a motor frame and gear housing; a pinion for engaging the gear of an engine to be started; a motor switch; a pivot rod supported by the gear housing; a pinion-shifting lever pivoted on said rod and having spaced arms connected by a yoke; a pedal lever coaxial with the pinion-shifting lever and having an arm located between the arms of the pinion-shifting lever; and means for connecting the levers including a rod connected with the pedal-lever arm and extending through an opening in the yoke of the shifting lever, a shoulder member on the rod, and a coiled spring surrounding the rod and located between the shoulder member and the pinion-shifting lever.
4. Engine starting apparatus comprising, in combination, a pinion adapted to move into engagement with and drive a gear connected with an engine to be started or to be driven thereby when the engine becomes self-operative; a motor; driving connections between the motor and pinion including means whereby the pinion can be automatically demeshed from the engine gear when the engine becomes self-operative; manually operable means for moving the pinion into engagement with the engine gear, said means including a pedal, two movable members one connected with the pedal and the other with the pinion, a latch plate yieldingly connected with one member, and a latch for engaging said plate connected with the other member; means for moving the latch out of engagement with the plate after the meshing of gears by the movement of said members; and means operated by the pedal for controlling the motor.
5. Engine starting apparatus comprising, in combination, a pinion adapted to move into engagement with and drive a gear connected with an engine to be started or to be driven thereby when the engine becomes self-operative; a motor; driving connections between the motor and pinion including means whereby the pinion can be automatically demeshed from the engine gear when the engine becomes self-operative; a pedal operated lever; a pinion shifting le-
- ver; a latch plate yieldingly connected with one of the levers; a latch for engaging the plate connected with the other lever; a spring connected with the latch and normally biased to hold the latch in engagement with the plate, but biased by movement of the pedal to disconnect the latch from the plate after the pinion is meshed with the engine gear; and means operated by the pedal for controlling the motor.
6. Engine starting apparatus comprising, in combination, a pinion adapted to move into engagement with and drive a gear connected with an engine to be started or to be driven thereby when the engine becomes self-operative; a motor; driving connections between the motor and pinion including means whereby the pinion can be automatically demeshed from the engine gear when the engine becomes self-operative; a pedal operated lever; a pinion shifting lever; a latch plate spring-connected to the pinion lever; a latch for engaging the plate connected to the pedal lever, a spring connected with the latch and normally biased to hold the latch in engagement with the plate, but biased by movement of the pedal to disconnect the latch from the plate after the pinion is meshed with the engine gear; and means operated by the pedal for controlling the motor.
7. Engine starting apparatus comprising, in combination, a pinion for engaging the gear of an engine to be started; a motor for driving the pinion; a motor switch; and manually-operable means for moving the pinion into engagement with said engine gear and for closing the switch, said means including a pedal-operated lever; a pinion-shifting lever, means for transmitting motion from the pedal lever to the pinion-shifting lever comprising a yieldable member and means for detachably connecting the yieldable member with the pedal lever.
8. Engine starting apparatus comprising, in combination, a motor; connections between the motor and engine including a pinion adapted to engage a gear connected with an engine to be started, and means whereby the pinion may be automatically demeshed from the gear when the engine becomes self-operative; manually-operable means for moving the pinion into engagement with the engine gear, said means including a pedal, two movable members, one connected with the pedal and the other with the pinion, a latch plate yieldingly supported on one of said members, and a latch pawl pivotally supported on the other of said members and adapted to engage the latch plate; a spring engaging the latch, and normally biased to hold the latch in engagement with the plate, but biased by movement of the pedal, whereby to disconnect the latch from the plate after the pin-

ion is meshed with the engine gear; and means operated by the pedal for controlling the motor.

9. Engine starting apparatus comprising, in combination, a motor; connections between the motor and engine including a pinion adapted to engage a gear connected with an engine to be started, and means whereby the pinion may be automatically demeshed from the gear when the engine becomes self-operative; a pedal; coaxially-mounted levers, the one of which is connected to the pedal, the second to the pinion, said second lever including an apertured yoke portion; a latch plate yieldingly supported on the yoke portion of the second lever so as to cover a portion of the aperture therein; a latch pawl pivotally carried by the first lever and adapted to extend into the aperture of the second lever to engage the latch plate; a spring engaging the latch and normally biased in one direction to hold the latch in engagement with the plate, but adapted to be biased in the opposite direction, by movement of the first lever, whereby the latch pawl will be unlatched from the plate after the pinion is meshed with the engine gear; and means operated by the pedal for controlling the motor.

10. Engine starting apparatus comprising, in combination, a motor; connections between the motor and engine including a pinion adapted to engage a gear connected with an engine to be started, and means whereby the pinion may be automatically demeshed from the gear when the engine becomes self-operative; a pedal; a rod supporting levers, the one of which is connected to the pedal, the second being connected to the pinion; a latch plate yieldingly supported on one of said levers; a latch pawl pivotally supported on the other of said levers, said pawl being adapted to engage with the latch plate; a spring normally adapted to urge the latch pawl into engagement with the latch plate, but biased to urge the pawl out of latch-plate engagement, by the movement of the pinion into gear-engaging position; a spring including a loop extending about the latch pawl and engaging with the latch plate, and having coiled portions surrounding the rod supporting the levers, the free ends of said spring being anchored to the motor; and means operated by the pedal for controlling the motor.

In testimony whereof I hereto affix my signature.

FRANK H. PRESCOTT.
